UNITED STATES PATENT OFFICE.

ARTHUR PENTECOST, OF EAST ORANGE, NEW JERSEY, ASSIGNOR TO WALES ADDING MACHINE COMPANY, OF WILKES-BARRE, PENNSYLVANIA, A CORPORATION OF PENNSYLVANIA.

CALCULATING-MACHINE.

1,342,969.

Specification of Letters Patent. Patented June 8, 1920.

Application filed May 15, 1918. Serial No. 234,650.

To all whom it may concern:

Be it known that I, ARTHUR PENTECOST, a subject of the King of England, residing at East Orange, Essex county, New Jersey, have invented new and useful Improvements in Calculating-Machines, of which the following is a specification.

More particularly, this invention relates to indexing mechanisms for calculating machines.

Generally, in the key-set, shaft-operated type of machine to which this invention is directed, a plurality of denominational trains of mechanism are provided, each including a row or series of stops, a rack or positioning bar, the extent of travel of which is controlled by any of the stops in the correlated row, a typecarrier provided with types corresponding to the individual stops of the row, which types are positioned at the printing line in accordance with the particular stop then effective, and a numeral wheel to coat with the rack.

Keys control the projection of the stops to effective position, and in the form of machine herein set forth, there is a denominational row of keys for each row of stops, although the use of the invention is not restricted to this keyboard arrangement.

Depression of keys corresponding to the item desired to be registered and printed, sets the proper stops of the corresponding denominational rows, in the paths of the correlated racks or positioning bars, and denominational latches common to the stops in the respective rows, hold the projected stops in set position.

After the registration and printing of the item has taken place, a universal latch-releasing mechanism is actuated to trip all the latches whereby to release the set stops to return to normal idle position, notwithstanding the fact that some of the same stops may be required in the setting up of the next item, which necessitates the re-depression of keys depressed in the previous operation.

In straight adding operations this works no particular hardship, as only an occasional digit may be repeated in the same denomination in two or more successive operations.

In many cases, however, it is desired to set up and print a date, for instance, coincidentally with each amount, for which purpose the printing section of the machine is

split in the well known manner at the desired point, and the left hand typecarrier is equipped with types to print abbreviations of the months.

Under this arrangement the operator may set up a date and an amount on the keyboard, which date and amount will be printed simultaneously with no intervening ciphers, due to the split in the printing section.

In some classes of work, the operator desires to print the same date repeatedly, with a series of different items, particularly in ledger posting, wherein a leaf is inserted in the machine, a single date and amount printed thereon, and the leaf removed to permit the insertion of another leaf, on which the same date with probably a different amount is to be printed.

In such event, it is unnecessary to restore the stops controlling the date printing at every operation of the main drive shaft, and considerable time is thereby saved.

This is only one of a number of applications of the present invention, an object of which is to provide novel means to enable the automatic release of the locking means which retains the stops set in certain denominations of the field of stops, without affecting the locking means for the stops set in other denominations of the field.

Another object is to enable the operator to control at will the restoration of the stops in two or more sections of the field of stops, so that at his option, all the projected stops will be returned at every operation of the main drive shaft, or the stops in one section of the field maintained in effective position while the stops in another section are freed to return to idle position.

In this manner, the operator may effect a split in the field of denominational rows of stops at a point corresponding to the split in the printing section.

Thus, assuming that a machine adapted for nine denominations is equipped for date printing, the split in the printing section would be formed between the sixth and seventh typecarriers counting from the right, and the split in the indexing mechanism would be located between the sixth and seventh denominational rows of stops.

Obviously, the invention is applicable to machines equipped with more or less than nine denominational rows of stops.

In effecting the objects of this invention, I provide two separate latch-releasing devices to control the latches corresponding with the typecarriers on the opposite sides 5 of the split, respectively, and arrange a single actuator adapted to directly drive both latch-releasing devices, so that one is not operated through the other.

In addition, I provide means operable 10 at will, to disable one of the latch-releasing devices, whereby the latches controlled thereby may remain effective throughout repeated operations of the main drive shaft.

To these and other ends, my invention 15 comprises certain novel features and combinations of parts, all of which will be more fully set forth hereinafter and particularly pointed out in the claims.

In the accompanying drawings, Figure 20 1 is a side view (partly broken away) of the keyboard of the well known Wales calculating machines, equipped with one embodiment of the invention;

Fig. 2 is a fragmentary plan view 25 thereof, partly broken away;

Fig. 3 is a fragmentary rear end view, partly broken away;

Fig. 4 is a detail side view of a denominational train of mechanism to the left of the 30 split in the printer section, equipped to print month designations,

Fig. 5 is a disassembled perspective view of the main parts of this form of my invention, and

Fig. 6 is a detail view of one of the 35 numeral type carriers.

I have chosen to illustrate my invention as applied to the indexing mechanism of a Wales calculating machine, disclosed in U. 40 S. patents to Wales, 745,539, Dec. 1, 1903; 768,097, Aug. 23, 1904; and 797,032, Aug. 15, 1905; and to McFarland, 874,107, Dec. 17, 1907, to which reference is made for a more complete explanation.

45 A calculating and listing machine of this class comprises an indexing mechanism, an accumulating section, and a printing section.

The indexing section of the Wales machine is preferably a unit construction, 50 movably placed in the machine, and comprises a keyboard composed of side frames 110 (Figs. 1 and 4) connected by cross rods 101 and angular cross bars 118, the latter 55 arranged in stepped relation. Standards 110^a extending upwardly from the side frames, support a key plate 112 at a convenient incline. Keys 117 arranged in rows or denominations (Figs. 1, 2 and 3) from 60 front to rear of the keyboard, pass through apertures pierced in the keyboard plate 112 and through registering guide slots formed in the angle bars 118. Springs 180 encircle the stems 117, the lower ends of which 65 springs rest on the angular cross bars 118

and the upper ends of which engage shoulders on the keysystems 117 to restore the stems to, and sustain them in, normal raised position. Check lugs 117^a (Figs. 1 and 3) project from the sides of the keysystems above 70 the angular bars 118 to limit the depression of the keys, by contact with the bars 118, and similar check lugs (not shown) located on the stems 117 beneath the angular bars 118, arrest the stems when they reach their 75 normal positions under the influence of the springs 180.

As the rows or denominations of keys are alike, except as hereinafter specifically pointed out in connection with the row of 80 keys designating the months, an explanation of one row will suffice for all.

The lower ends of the stems 117 are pivotally connected to the forward ends of levers 116 (Figs. 1, 2 and 4) fulcrumed intermediate their ends on brackets 111 depending from the cross bars 101, and the rear ends of the levers are articulated with the lower ends of stops or index pins 115 arranged in denominational rows corresponding to the 90 rows of keys 117, the upper ends of which stops protude in file through guide apertures extending from front to rear in the top of a housing 113, supported on rearward extensions of the side frames 110. 95

The keysystems, preferably, are all of the same length, but the levers 116 are successively longer from top to bottom (Fig. 1) and the stops or index pins 115 are successively longer from front to back. 100

Obviously, depression of the rearmost key 117 against the tension of its spring 180, projects the foremost stop 115 above the remaining stops in the same row or file, and to maintain the stop projected, the edge of 105 each stop or index pin carries an ear 115^a (Fig. 3) adapted to coact with a locking device in the form of a latch 114 common to each denominational row of stops, and extending across the housing 113 from front 110 to rear. Pintles 114^a projecting from the lower corners of the latch, are journaled in the front and rear sides of the housing, and a spring 181 connected to a trip lug 114^b extending from the upper rear corner of the 115 latch, holds the free edge of the latch 114 against the adjacent edges of the stops 115 at a point above the ears 115^a thereof.

The ear 115^a, as the stop is projected upwardly, wipes past and displaces the associated latch 114 against the tension of its spring 181, which restores the latch to normal position, after the ear, in its ascent, escapes the latch, and upon removal of the pressure on the keystem 117, the restoring 120 spring 180 returns the key and stop until the ear 115^a contacts the upper edge of the latch, which prevents further return and holds the stop in effective position.

In case a key has been erroneously de- 130

pressed, depression of another key in the same denomination will cause its ear 115^a to rock the latch against the tension of its spring 181 to release the ear of the stop 115 controlled by the erroneously depressed key, whereupon, the restoring spring 180 withdraws the stop 115 from effective position and returns the erroneously depressed key 117 to normal.

10 This is what is known in the art as a flexible keyboard. If the key last actuated is gently depressed until the apex of its ear 115^a contacts the free edge of the latch 114 without passing above the latch, the key will 15 restore to normal when pressure thereon is removed, under the influence of the spring 180. Otherwise, the latch will swing beneath the ear to hold the second-named stop projected.

20 The individual stops 115 of each denominational row variously arrest the excursions of corresponding positioning bars and racks 310, 310^d (Fig. 4) pivotally mounted at 361^f and 350 on the upper ends of front supporting arms 312 and rear supporting arms 311, 311^d, respectively. The front supporting arms are journaled on a cross shaft 300 and the rear supporting arms are journaled on a cross rod 301. Drive springs 383 connected to the rear supporting arms 311, 311^d, and to a restraining and restoring bar 205, tend to advance the forwardly projecting ends of the racks and positioning bars toward the stops 115. The restraining and restoring bar 205 is supported in fingers 266^m, on a rotatable cross bar 266, and normally lies in the path of the front arms 312 to hold the racks and positioning bars in re-tired position.

40 The main drive shaft 200 on its forward stroke, rocks an arm 210 whose free end traverses a cam slot in a crank 220 connected to the cross bar 266, to withdraw the restraining and restoring bar 205 and free the arms 312 and 311, 311^d to the action of the springs 383, which advance the racks 310 and positioning bars 310^d until they are arrested by projected stops 115 or by rack detents similar to the detent 221^m shown, in 45 those denominations wherein no stops have been projected.

The denominational rack detents which overlie the upper ends of the stops in each row, are journaled on a cross shaft 202, and 50 are displaced or shifted out of the paths of the racks and positioning bars by the projection of stops in the corresponding denominational rows.

Converging levers 311^a extend rearwardly 60 from the respective rear supporting arms 311, 311^d. Links 515, 523^f connect the converging levers 311^a to the lower ends of the respective typecarriers 514 and 524^a in the heads of which are mounted the types 561.

65 As the rear arms 311, 311^d swing for-

wardly during the advance of the racks 310 and positioning bar 310^d, the converging levers 311^a rise and lift the typebars 514, 524^a to locate the types 561 corresponding to the keys depressed, at the printing line 70 on the platen 2094, and as the main drive shaft 200 approaches the limit of its forward stroke, printing hammers (not shown) impress the types on the paper carried by the platen.

75 Denominational numeral wheels 490 individually rotatable on an axle 400, each carry a pinion 435 arranged above the respective racks 310. Suitable mechanism (not shown) normally supports the numeral 80 wheels and their pinions above the racks 310, in which position, they are held during the advance of the racks and positioning bar. The main drive shaft, as it reaches its forward limit of rotation, trips the numeral 85 wheel supporting mechanism to effect the engagement of the numeral wheel pinions with their racks.

The main drive shaft, on its return stroke, 90 presses the restraining and restoring bar 205 against the advanced forward supporting arms 312 to retire the racks and positioning bar.

95 The racks, during such retirement, turn the numeral wheels 490 to register thereon an amount corresponding to the values of the depressed keys and projected stops, and as the main drive shaft nears the end of its return stroke, subsequently to the complete retirement of the racks, it operates the counter-supporting mechanism, to disconnect the numeral wheel pinions from the racks.

100 The racks 310 and positioning bar 310^d, during their retirement, restore the typecarriers 514, 524^a to their normal lowered 105 positions.

110 For a more complete explanation of the foregoing, reference may be made to U. S. patents to Wales, 797,082, above mentioned, and to Wilgus, 1,133,596, March 30, 1915.

115 The latches 114 which hold the key-set stops 115 in effective position are released ordinarily by the main drive shaft 200 during its return stroke, to enable the springs 180 to restore the keys 117 and stops to idle position preparatory to setting up another item, in the following manner.

120 The trip lugs 114^b on the latches extend outwardly through apertures 113^a (Fig. 3) in the rear wall of the housing 113, into the paths of denominationaly arranged releasing tappets 252 (Figs. 1, 2 and 4) preferably equipped with anti-friction rolls 239, and projecting radially from a suitably journaled universal latch-releasing bail 201 125 lying adjacent all the trip lugs 114^b.

130 An arm 224 (Figs. 1 and 4) fastened to the releasing bail 201, is pivotally connected at 264^f to one end of an actuator comprising a thrust link 223, the opposite end of which

link has an enlarged aperture 223^a fitting over and resting upon a stud 260^c mounted on the side frame (not shown) of the machine. Preferably, the link or actuator is 5 guided at its lower end by a grooved roll 243 journaled on the stud 260^c, and a spring 284 connected to the arm 224, tends to hold the latter advanced, and the releasing tappets 239 below the trip lugs 114^b, as shown 10 in Figs. 1 and 4.

A shoulder 223^b on the link or actuator 223 lies in the path of a tripping stud 255 mounted on a crank 212 fast on the main drive shaft 200.

15 The tripping stud 255, during the forward stroke of the main drive shaft, wipes idly beneath the shoulder 223^b of the releasing link or actuator 223, lifting and then dropping the lower end of the latter, the 20 aperture 223^a being made large enough to accommodate this idle shifting. The main drive shaft, on its return stroke, rocks the crank 212 rearwardly to cause the trip stud 225 to strike the shoulder 223^b and thrust 25 the link or actuator 223 rearwardly against the tension of spring 284, which thrust is transmitted as a rocking movement through the arm 224, to the universal bail 201, to turn the bail and contact the tappets 252, 30 239, with the projecting trip lugs 114^b of the latches 114. The tappets swing the latches 114 away from the ears 115^a on the stops 115, whereupon the restoring springs 180 retract the stops to idle position, and 35 restore the depressed keys 117.

The tripping stud 255, during the continuation of the return stroke, escapes past the shoulder 223^b, whereupon, the spring 284 restores the actuator 223 and latch-releasing mechanism 201, 239 to normal idle position.

A spring 581, inferior in strength to spring 284, holds the thrust link or actuator 223 down to insure that the shoulder 223^b shall lie in the path of the tripping stud 255.

The foregoing construction is old and only constitutes a part of the present invention in so far as it is combined with the 50 novel features hereinafter set forth.

It will readily be seen that by removing certain of the denominational releasing tappets 252, 239, any stops 115 set in corresponding denominations will not be restored, at each operation of the main drive shaft, but will remain in position to arrest the corresponding racks or positioning bars 310, 310^a, with the result that the data represented by the projected stops will be 55 cumulated and printed as often as the main drive shaft is operated. And this in effect, is what I have done, but as it is also necessary to restore these stops to idle position when it is desired not to repeat the data controlled thereby, I have provided a second 60

latch-releasing means independent of the universal bail 201 and its releasing tappets, and operable directly from the driving link or actuator 223, which actuates the releasing bail 201.

70 While the invention is susceptible of use in several ways, I have chosen to illustrate its operation in connection with the well known statement keyboard comprising denominational rows of numeral keys 117 extending toward the left of the keyboard. The last row of keys at the left of the machine (Figs. 1, 2 and 3) are similar to the regular numeral keys 117, except that the key tops bear abbreviations of the months 75 from January to September. The series of stops 115 controlled thereby, are similar to the denominational rows of stops controlled by the regular numeral keys and serve to variously arrest a positioning bar 310^a similar 80 to the familiar racks 310, except for the omission of the rack teeth, such bar being connected with a typecarrier 524^a similar to the regular typecarrier except that it mounts the twelve types for abbreviations of the 85 months. As there are but nine keys to a denominational row, the three uppermost keys in the second denominational bank from the left are equipped with key tops bearing abbreviations of the months from October to 90 December.

95 In view of the fact that a single typecarrier 524^a carries the twelve month designation types, the upper ends of the stops 115^b (Fig. 3) controlled by the month keys in the second row from the left do not protrude through the housing 113 in alignment with their controlling keys, but extend laterally and then upwardly so that their extreme upper ends protrude through the top 100 of the housing 113 at points adjacent the stops 115 in the left hand bank, to arrest the positioning bar 310^a connected with the month typecarrier 524^a. The positioning bar carries a laterally extending lip 310^c 105 (Fig. 2) to contact the three offset month stops 115^b. The stops 115^b have legs 115^c (Figs. 2 and 3) interspaced between the stops 115 of the left hand row, and equipped with ears 115^a with which the left 110 hand latch 114 coacts. Thus, a single latch locks any of the month stops 115, 115^b in effective position, and all the month stops 115 coact with a single rack detent 221^m (Fig. 4) 115 and define the excursions of a common positioning bar 310^a.

120 The numeral keys 1, 2 and 3 (not shown) in the second row from the left, are used to set up the tens digits of the days of the month, and the numeral keys 117 in the third row from the left, set up the stops 115 controlling the printing of the units digits of the days of the month.

125 With this form of keyboard, the well known split in the printer section (shown 130

in U. S. patent to Wilgus, 1,260,615, March 26, 1918) may be formed at will between the third row of keys from the left and the remaining rows to the right thereof.

5 Also, as the registration of months on the counters 490 is of no value, the numeral wheel corresponding with the left hand denomination of keys (now appropriated to the printing of month designations) is omitted.

10 Omission of the releasing tappers 252, 239 to coact with the latches 114 for the three left hand denominations, as shown in Fig. 2, permits the repeated printing of any 15 date set up on the three left hand denominations, with successive amounts set up on the banks or denominations to the right of the split, without requiring the operator to set up the anew prior to every operation of the 20 main drive shaft, thereby relieving the operator of this extra and unnecessary work, and enabling him to confine his attention to the correct setting up of the amounts.

Obviously, when it is desired to use the 25 keyboard to capacity, the split is eliminated and the numeral keys in the second and third banks from the left may be employed to set up stops corresponding to the digits to be registered in those denominations. Such 30 use would render advisable the automatic release of the stops 115 in the second and third denominations from the left, at every operation of the main drive shaft.

Furthermore, even when the machine is 35 split and the three left hand banks or denominations are used to set up dates, it is desirable to provide means whereby the stops 115, 115^b controlling date printing, may be released at each operation of the 40 main drive shaft when such action is required.

Therefore, I provide an auxiliary latch-releasing device comprising a lever 129^b having a hub 133 (Figs. 2 and 3) journaled on 45 a sleeve 130^a (Figs. 1 and 4) projecting outwardly from the left hand side frame 110. The rear arm of the lever 129^b projects past the rear wall of the housing 113 and is offset, as at 129^c, which offset normally lies beneath the projecting trip lugs 114^b of the three left hand latches 114 and is provided with protuberances 129^d in line with the trip lugs. A spring 187 connected to a depending arm 129^e of the lever, normally holds 50 the releasing offset 129^c in idle position, and the forward arm of the lever carries a lip 129^f adapted to contact one of the standards 110^a of the side frame 110, to arrest the lever in idle position against the tension of 55 the spring 187.

An adjustable finger 129 pivoted intermediate its ends at 460, to the depending arm 129^e of the lever 129^b, carries a laterally extending foot 129^g at its forward end, 60 which normally confronts a drive stud 354^b

(Figs. 1 and 4) projecting laterally from the actuator 223. A spring 185 connected to a stop lip 129^h on the finger 129, holds the latter in effective position (Fig. 4), the stop lip contacting the edge of the depending 70 arm 129^e to arrest the throw of the finger in one direction.

Normally, upon the return stroke of the main drive shaft 200, the crank 212 and stud 255 drive the actuator 223 rearwardly to 75 rock the universal latch-releasing bail 201, and at the same time, force the pin 354^b against the foot 129^g of the finger 129 to rock the releasing lever 129^b and contact the protuberances 129^d with the trip lugs 114^b 80 of the three left hand denominational latches 114 to swing the latter and thereby release the set stops 115, 115^b for restoration by the springs 180.

Whenever it is desired to repeat the data 85 set up by depression of keys 117 in the three left hand banks, a disabling key 129^a, slotted to embrace the sleeve 130^a is depressed and locked by engaging the notch 129ⁱ (Fig. 4) thereof with the keyboard plate 112. 90 Depression of this disabling key 129^a forces a cam 129^k thereon against the stop 129^h of the adjustable finger 129, to swing the finger on its pivot 460 and displace the foot 129^g from the path of the stud or projection 354^b 95 on the actuator 223 to thus render idle the auxiliary latch-releasing lever 129^b.

Under this adjustment, the date set up by the depression of keys 117 in the three left hand banks can be repeated as often as desired, and while the latches 114 which hold the stops 115 to the right of the three left hand banks, are released by the bail 201 and the tappers 252, 239, at each operation of the main drive shaft 200, the latches coacting 100 with the stops 115, 115^b controlled by the three left hand banks of keys 117 remain effective to hold the stops in set position until the next operation of the main drive shaft after the disabling key 129^a is released.

Another advantage pertaining to the use of this mechanism, with flexible keyboard, is that the stops 115, 115^b controlling the date printing can be released from the 115 latches 114 by the depression of other date-designating keys in the three left hand banks, to change the date without necessitating the restoration of the disabling key 129^a. Thus, should the operator wish to change the date 120 being printed from "Jan. 12" to "Feb. 27," for instance, all that is necessary is to depress the keys 117 corresponding to the latter date, whereupon the stops 115, 115^b corresponding to the former date will restore to 125 idle position and the latches 114 will lock the stops corresponding to the latter date in projected position.

A spring 186 restores the disabling key 129^a to idle position upon the release of the 130

notch 129¹ from the keyboard plate 112. A set collar 134 on the end of the sleeve 130^a prevents the disengagement of the disabling key 130^a and the lever 129^b therefrom, the 5 set collar, and a spacing washer 135 between the lever and key, operating to guide the latter as it is depressed and restored.

While I have explained my invention as applied to the three left hand banks of keys 10 only, it is obvious that it may be variously arranged to control a larger or smaller number of banks as desired, and I do not wish to limit myself to the exact construction shown.

15 Changes may be made in the form and arrangement of the several parts set forth, without departing from the spirit and scope of my invention.

What I claim as new is—

20 1. The combination with an indexing mechanism, including several denominational files of stops; means to set the stops to effective position; and means to releasably retain the set stops in effective position; of 25 separate and wholly independent stop-releasing members; a single actuator common to the several stop-releasing members, and directly connected with one of the stop-releasing members; a shiftable finger connected to another of the stop-releasing members and normally lying in the path of the actuator to enable the latter to directly drive the last named stop-releasing member, independently of the first named stop-releasing member; and means to shift the 30 finger out of the path of the actuator.

35 2. The combination with an indexing

mechanism, including several denominational files of stops; means to set the stops to effective position; and means to releasably retain the set stops in effective position; of 40 separate and wholly independent stop-releasing members; a single actuator common to the several stop-releasing members, and directly connected with one of 45 the stop-releasing members; a projection mounted on the actuator to directly drive another of the stop-releasing members; a finger shiftably mounted on the last named stop-releasing member, and normally lying 50 in the path of the projection; and means to displace the finger relatively to the projection, to render inoperative the last-named stop-releasing member.

3. The combination, in a calculating machine, with an indexing mechanism, including a plurality of denominational files of stops; means to set the stops to effective position; and latches to releasably hold the set stops in effective position; 60 of a latch-releasing mechanism, including a rocking member lying adjacent the latches; tappets mounted on the rocking member to contact and disable certain only of the latches; an auxiliary latch-releasing lever 65 supported independently of the rocking member, and lying adjacent certain other latches; means to actuate the rocking member; and a finger connected with the auxiliary latch-releasing lever, and adjustable 70 into and out of the path of the means which actuates the rocking member.

ARTHUR PENTECOST.
